[57] **CLAIM**

The ornamental design for a sock, as shown and described.

DESCRIPTION

FIG. 1 is a front perspective view of a sock showing our new design;

FIG. 2 is a side elevational view thereof;

FIG. 3 is an opposite side elevational view thereof;
FIG. 4 is a front elevational view thereof;
FIG. 5 is a rear elevational view thereof, the pattern is intended to represent the number 33;
FIG. 6 is a top plan view thereof;
FIG. 7 is a bottom plan view thereof;
FIG. 8 is a front perspective view of a second embodiment of a sock showing my new design, the difference being the open calf portion;
FIG. 9 is a side elevational view thereof;
FIG. 10 is an opposite side elevational view thereof;
FIG. 11 is a front elevational view thereof;
FIG. 12 is a rear elevational view thereof;
FIG. 13 is a top plan view thereof;
FIG. 14 is a bottom plan view thereof;
FIG. 15 is a front perspective view of a third embodiment of a sock showing my new design, the difference being the bow on the top band;
FIG. 16 is a side elevational view thereof, the opposite side is a mirror image;
FIG. 17 is a front elevational view thereof;
FIG. 18 is a rear elevational view thereof;
FIG. 19 is a top plan view thereof;
FIG. 20 is a bottom plan view thereof;
FIG. 21 is a front perspective view of a fourth embodiment of a sock showing my new design, the difference being the bow on the top band and the piping around the open calf portion;
FIG. 22 is a side elevational view the opposite side is a mirror image;
FIG. 23 is a front elevational view thereof;
FIG. 24 is a rear elevational view thereof;
FIG. 25 is a top plan view thereof; and,
FIG. 26 is a bottom plan view thereof.
